Primary Examiner — Jack Reickel*Assistant Examiner* — Salamah Jordan(74) *Attorney, Agent, or Firm* — Patterson Intellectual Property Law, P.C.; Jerry Turner Sewell(57) **CLAIM**

The ornamental design for a vibrating fitness roller, as shown and described.

DESCRIPTION

FIG. 1 is a front perspective view of a vibrating fitness roller of the present design;

FIG. 2 is a rear perspective view thereof;

FIG. 3 is a top view thereof, the bottom view, the left side view and the right side view being mirror images thereof;

FIG. 4 is a front view thereof; and,

FIG. 5 is a rear view thereof.

The broken lines in the drawings are for the purposes of illustrating portions of the vibrating fitness roller, which form no part of the claimed design.

1 Claim, 4 Drawing Sheets(56)
